UNITED STATES PATENT OFFICE.

FRANK L. GOHEEN, OF GROUSE, IDAHO.

TELEPHONE SYSTEM.

1,270,723.

Specification of Letters Patent. Patented June 25, 1918.

Application filed June 5, 1917. Serial No. 173,001.

To all whom it may concern:

Be it known that I, FRANK L. GOHEEN, a citizen of the United States, residing at Grouse, in the county of Custer and State 5 of Idaho, have invented certain new and useful Improvements in Telephone Systems, of which the following is a specification.

This invention has relation to party line telephone systems, and has for an object 10 to provide an apparatus, and method of wiring the same for use in subscribers' stations of a party line telephone system whereby to prevent eavesdropping of un-called subscribers upon those conversing. 15 Another object of the invention is to provide an apparatus for party telephone systems whereby subscribers of the same party line may converse with each other without interference, and whereby any subscriber of 20 a party line may converse with another through the central office without interference by any other subscriber of the party line.

A still further object of the invention is 25 to provide an apparatus for party line telephone systems whereby the bell of each subscriber's set will be energized when any subscriber is called but whereby only the party called will be placed in communication with 30 calling subscriber, the remaining subscribers being shut out by my apparatus.

A still further object of the invention is 35 to provide means in a party line telephone apparatus of the character above stated whereby the fact that the party line is in use may be indicated and whereby the number of the called subscriber may be known.

In addition to the foregoing my invention 40 comprehends improvements in the details of construction and arrangement of parts to be hereinafter more fully described and particularly set forth in the appended claims.

In the accompanying drawings in which 45 similar and corresponding parts are designated by the same characters of reference throughout the several views in which they appear:—

Figure 1, is a diagrammatic view illustrating 50 the wiring of a party line telephone system and the method in which my apparatus is incorporated therein and the various parts of the apparatus correlated.

Fig. 2, is a vertical section taken through 55 the apparatus box of a subscriber's set illustrating the parts of my apparatus.

Fig. 3, is a view in section taken on the line 3—3 of Fig. 2.

Fig. 4, is a detail section taken on the line 4—4 of Fig. 2 and

Fig. 5, is a detail view of the locking out 60 disk.

With reference to the drawings, particularly Figs. 2 and 3, 10 indicates generally the instrument box of a subscriber's set which is mounted upon a base board 11 and is provided with the usual removable base plate 12, in the present instance said base plate having an opening 13 formed therein. A horizontal shaft 14 is provided journaled at its rear end in a step bearing 15 mounted 70 upon the base board 11 within the instrument box, with the front end of the shaft journaled centrally in the disk 16 which is mounted upon the rear face of the front plate 12 of the instrument box through the 75 medium of lateral extensions 17 formed at uniformly spaced points upon the periphery of said disk. A metallic sleeve 18 is encompassed about the shaft 14, said sleeve however, being shorter than the shaft so as, 80 to space the end of the sleeve inwardly from the ends of the shaft as indicated. The sleeve 18 is furthermore spaced from the shaft through the provision of a tube 19 of insulating material interposed therebetween as indicated.

Mounted upon the forward end of the sleeve 18 and in spaced relation to the disk 16 is a locking out disk 20 fixedly secured to the sleeve through the medium of a set 90 screw 21 which enters a central boss formed upon the disk and engages the sleeve. Extending parallel to the shaft 14 thereabove is a slidable rod 22 disposed in close proximity to the periphery of the disk 20 with the forward end of the rod projected 95 through a bushing placed upon the front plate 12 of the instrument box and provided with a button 23 whereby the rod may be reciprocated. Fixedly secured to the rod 22 100 is a disk 24 which, by engagement with the periphery of the disk 20 serves to prevent inward movement of the rod 22 except when a semi-circular notch 25 formed upon the periphery of said disk 20 is disposed by rotation of said disk 20 in a position to permit the disk 24 to pass through said notch. The rear end of the rod 22 is guided for movement in a bushing 26 mounted upon the base board 11. A disk of insulating material 27 110

is also mounted upon the rod 22 adjacent the rear end of the rod for engagement with a resilient contact finger 28 mounted upon the inner top side of the instrument box, said finger being adapted for engagement with a finger 29 insulated from the finger 28 as indicated.

With reference to Fig. 1 of the drawings wherein I have indicated a diagrammatic view of a party line telephone system and the embodiment of my apparatus therein, A. B. and C. indicate subscribers' stations and D, indicates the central office in communication with said subscribers. With reference to the diagrammatic view, 30 and 31 indicate the main leads which are connected at the central office to a jack 32. The main leads are energized by means of a battery 33 in the central office, the current however traversing an electromagnet 34 forming part of a relay, the armature of which is designated 35. The armature is connected by means of a conductor 36 to the source of current, and when the armature is attracted by the magnet is adapted to place the source of current in communication with a conductor 37 having a small lamp 38 connected in series thereto. A manually operable magneto 39 may be provided for energizing the system to sound the various polarized bells.

Considering one of the subscribers' stations, 40 indicates the primary of an induction coil which is connected at one of its terminals 41 to the main lead 30 and by means of its other terminal to one of the terminals of the secondary 42. The other terminal of the secondary is connected to a receiver 43 having its other terminal 44 placed in communication with a conductor 45 which is connected at one end to the connected terminals of the primary and secondary of the induction coil, and at its opposite end to the contact finger 28 mentioned above. The coacting contact finger 29 is placed in communication with the transmitter 46 of the set, by means of a conductor 47 having a source of current 48 interposed therein, the other point of connection of the transmitter being placed in communication by means of a lead 49 with the main lead 31 of the system.

The disk 16 mentioned above in each subscriber's instrument box is provided with a plurality of pairs of circumferentially arranged contacts indicated in station A at 50^a and 51^a, in station B at 50^b, 51^b, etc. Referring to station A the contact 50^a is connected by means of a conductor 52 to the conductor 45 which leads to the contact finger 28 as indicated. It will also be noted that the contact 51^a is placed in communication with the main lead 30 of the system by means of a conductor 53. Referring to Fig. 2 of the drawings 54 indicates a contact arm

which is fixedly mounted upon the shaft 14 and is adapted for engagement with one of each pair of contacts mounted upon the disk 16. A similar contact arm 55 is also mounted upon the forward terminal of the metallic sleeve 18 for contact with the other contact of each pair of said contacts, the arms 54 and 55 being disposed in angular relation for that purpose. To energize the said arms 54 and 55, a contact finger 56 is mounted upon a block 57 secured to the base part of the instrument and is adapted for frictional contact with the rear end of the sleeve 18, a similar finger 58, mounted in a similar manner upon a block 59 being adapted for frictional contact with the rear end of the shaft 14. As indicated in the diagrammatic view, the arm 54 is placed in communication through the medium of its contact finger 58 with the above mentioned conductor 47 through the medium of a lead 60. The arm 55 is also placed in communication, through the medium of its contact 56 with the main lead 31 of the system by means of a conductor 61.

Referring particularly to Fig. 3 of the drawings 62 designates a ratchet wheel which is fixedly mounted upon the sleeve 18. The said ratchet wheel, and consequently the shaft 14, sleeve 18 and disk 20 and arms 54 and 55 are rotated intermittently by means of an arm 63 fulcrumed as at 64 upon a plate 65 which is secured to the inner face of one vertical wall of the instrument box. The free end of the arm 63 is movable in proximity to the periphery of the ratchet wheel 62 and is provided with a pawl 66 fulcrumed as at 66 upon the said arm 63 for engaging the teeth of the ratchet wheel. The pawl is held in such engagement by means of a light spring 67 which engages the pawl and which is mounted upon the arm 63, and movement of the pawl caused by contact therewith of the spring 67 is limited, by means of a lateral extension 68 of the pawl which engages the arm as indicated. An extension 69 is formed upon the plate 65 and which projects above the arm 63 for the purpose of carrying an adjustable stop 70 in the nature of a set screw which engages the arm 63 to limit its upward movement, said upward movement of the arm being produced by means of a light coil spring 71 connected at one end to the arm and its opposite end to an extension formed upon the extension 69. The arm 63 carries an armature 72 which is in a position to be attracted by an electromagnet 73 mounted upon an extension 74 of the base plate 65. An arm 75 is extended from the base plate and carries a pawl 76 for engaging the ratchet wheel to prevent rearward movement thereof, a stop 77 being provided to limit movement of said pawl and a spring 78 to retain the pawl in

- proper engagement with the ratchet wheel. With reference to the diagrammatic view it will be seen that the electromagnet 73 is connected by means of one of its terminals 79 to the main lead 31 of the system, while the other terminal is connected by means of a conductor 80 with an auxiliary lead 81 which extends parallel to the leads 30 and 31 and serves to connect only the subscribers 10 of a party line. If desired, however, the lead may be extended to the central office as indicated in the diagram.
- Each subscriber's set is provided with a switch or contact maker in the nature of a strip of resilient material 82 mounted at one end upon a block of insulation secured to the inner face of the vertical wall of the instrument box, the free end of the strip having a button 83 which extends through 20 an opening in the instrument box as indicated. The strip 82 when moved by means of the finger pressed upon the button 83 is adapted for contact with a stirrup 84. It will be seen in the diagrammatic view that 25 the auxiliary lead 81 is adapted to be placed in communication at any subscriber's station by means of a conductor 85 which may connect the auxiliary lead 81 to the stirrup 84, and a conductor 86 which may connect 30 the spring arm 82 with the said sleeve 30. The polarized bell 87 of each subscriber's station is connected across the leads 30 and 31 by means of a conductor 88 having interposed therein a condenser 89 after the usual fashion. Each subscriber may also energize the line for the purpose of ringing the polarized bells by means of a manually operable magneto generator 90 connected across the leads 30 and 31 as indicated.
- 40 In operation, the disks 20 of each subscriber's station, are positioned with their notches 25 in a position to permit the disk 24 to pass therethrough so that the rods 22 may be pressed inward as mentioned above. This is the normal position of the lock out mechanism. It will be noted from the diagrammatic view that in subscriber's station A the leads 52 and 53 are connected to the first pair of contacts 50^a and 51^a as indicated.
- 45 In station B however, the said leads 52 and 53 are connected to the next pair of contacts indicated at 50^b and 51^b. This is continued around the circumference of the disk 15 with each subscriber, that is the mentioned leads 53 and 54 in each subscriber's station are connected to a different set of contacts.
- Assuming that station B is calling up station A, the first act is to press the button 23 which is done by subscriber B. The rod 22 50 of said subscriber B must then be moved so as to dispose the disk 24 behind the disk 20, said disk 24 passing through the notch 25; and the contact fingers 28 and 29 brought into engagement by engagement therewith 65 of the insulated disk 27. While the button 23 is retained in an inward position against the tension of the resilient finger 28, the button 83 of subscriber B is pushed inward so as to place the leads 85 and 86 in communication. If station A is called the button 83 70 is pressed but once, and as a result thereof current from the battery 33 of the central station is permitted to pass along the main lead 30 of the system to the lead 86 of station B, through the contact maker to the lead 85 into the auxiliary lead 81, and from thence through the conductors 80 of each subscriber's station in the party line, through each electromagnet 73 thereof, back through the main lead 31 to the source of current. 80 In this manner each electro-magnet 73 is energized throughout the party line and as a consequence the ratchet wheel 62 will be rotated through a partial revolution in an obvious manner. It will therefore be seen that 85 the arms 54 and 55 will be rotated through a partial revolution to dispose the terminals thereof in contact with the first set of contacts of each subscriber's station. However, since in the present instance station A has 90 been called, the first set of contacts will be engaged by the arms 54 and 55, and it is only in station A that these contacts are alive. Owing to the fact that the disk 20 of each subscriber's station have been rotated, including station B (which is the calling station) the disk 24 of said calling station will be locked behind the disk 20 and the button 23 may then be released, such locking of the mechanism serving to retain 100 the fingers 28 and 29 in mutual engagement. Subscriber B having thus selected his station, he energizes the system by manipulating the magneto generator 90 so as to energize all the polarized bells. Subscriber A 105 responding to his ring may hear subscriber B owing to the fact that voice currents are set up in the talking circuit by means of the transmitter 46 of station B, said talking circuit proceeding from said transmitter 110 through the battery 48 of said station, through the conductor 47 to the contact finger 29, through the contact finger 28 and the conductor 45, through the primary coil 40, thence through the main lead 30 of the system to the primary coil 40 of station A, setting up oscillations in the induction coil, which are transformed by means of the secondary coil 42 into currents which are reconverted into sound waves by means of the 115 receiver 43. Following the current from the primary 40 of station A, the current proceeds through conductor 45 of said station, through conductor 52 to contact 50^a, through arm 55, returning by way of the lead 61 to the main lead 31 of the system, back to the transmitter 46 of station B. Subscriber A may converse with subscriber B in a similar manner, that is by means of variations of current 120 in the circuit set up by the transmitter 46 125 130

of station A. Said talking circuit proceeding from said transmitter through battery 48, conductor 60, through arm 54, into contact 51^a, through conductor 53 to the main lead 30 of the system, through conductor 41 and primary 40 of station B, setting up oscillations in the induction coil which are transmitted into the receiver 43 of station B, through conductor 45 to contacts 28 and 29 of station B, through conductor 47, returning to station A by means of the main lead 31 of the system. Thus, it will be seen, inasmuch as contacts 50^a and 51^a are alive only in station A, that station is the only one having a complete listening circuit with station B, the remaining stations in the party line being locked out inasmuch as the button 23 of the remaining station cannot be depressed because of movement of the disk 20 beyond a point wherein the notches 25 are disposed out of alignment with the disk 24, of the several stations. When the mentioned subscribers have finished talking, either may return the mechanism to normal position by repeatedly pressing the button 83 until arms 54 and 55 are returned to normal position which will dispose all of the disks 20 with their notches 25 uppermost, in the case of subscriber B, such movement of the disk permitting the disk 24 thereof to pass through the notch thereby permitting disengagement of the fingers 28 and 29 of said station. The position of the disks 20, arms 54 and 55, etc., may be known or made evident by means of an indicating hand 91 which may be mounted upon the forward extremity of the shaft 14 for movement over a dial plate 92 which may be placed behind the opening 13 of the front plate of the instrument box.

Any subscriber on the party line may call up central by pressing the button 23 so as to bring the contacts 28 and 29 into engagement whereby a circuit will be established from the source of current 33 of the central station, through the main lead 30 of the system, through the fingers 28 and 29 of the calling station, and back to the source of current at the central station by means of the return main lead 31. The magnet 34 in the relay of the central station will be energized so as to attract the armature 35 whereby to create a circuit from the source of current 33, through the lead 36, the armature 35 and conductor 37, through the incandescent lamp 38, and back to the battery causing said lamp to glow thereby indicating the fact that a subscriber is calling. The calling subscriber of the party line may thus be placed in communication with any party on another line by means of the jack 32. It will also be apparent that central may select any subscriber of the party line by depressing a button 83 provided for that purpose so as to energize the auxiliary lead 81

whereby to rotate the arms 54 and 55 and other elements movable therewith in each subscriber's station until the live contact 50^a, 51^a, etc., are engaged in the station selected. It will thus be apparent that no other subscriber on the party line may listen because of the fact that the arms 54 and 55 of such subscribers are not in a position to establish the circuit, and furthermore because the disk 20 of each subscriber's set are so arranged as to provide depression of any of the buttons 23 to establish a listening circuit. Thus, any party or the subscriber in a party line may have private conversation with a party or subscriber outside of the party line without interference as well as with any subscriber or neighbor of the party line without interference.

While I have illustrated and described my invention with some degree of particularity, I realize that in practice, various alterations thereover may be made, and I therefore reserve the right and privilege of changing the form of the details of construction, or otherwise altering the arrangement of the parts without departing from the spirit of the invention, or the scope of the appended claims.

Having thus described my invention, what I claim as new and desire to secure by Letters Patent is:—

1. In a party line telephone system, the combination with the main leads thereof, of a plurality of subscribers' sets, each set including a talking and a listening circuit, a switch at each set for connecting said talking and listening circuits, manually controlled means for actuating said switches, a rod, a disk having a peripheral notch, an enlargement on the rod adapted to pass through the notch to dispose the enlargement at the opposite sides of the disk when said disk is in a normal position, an auxiliary lead extending between the subscribers' sets, means at each subscriber's set for controlling energization of said auxiliary lead, means at each subscriber's set operable by energization of said auxiliary lead for intermittently rotating the disks whereby to dispose the notches out of alignment with the enlargement thereby preventing return of the switch actuated to open position and for preventing movement of the remaining switches to closed position, and means operable by rotation of the disks for connecting the talking and listening circuits of the called subscriber only with the main lead.

2. In a subscriber's set for a lock-out party line telephone system, the combination of a shaft mounted for rotation, a sleeve surrounding said shaft and insulated therefrom, a plurality of pairs of spaced contacts disposed around the shaft, an arm fixed to said shaft for contact with one contact of each pair, a second arm mounted on the

sleeve for contact with the other contact of each pair, brushes engaging the sleeve and shaft, a disk mounted on the sleeve and having a peripheral notch, a rod slidably adjacent the periphery of said disk, a disk forming an enlargement mounted on said rod, of a size sufficient to pass through the notch when the rod is reciprocated, a second enlargement on the said rod, and a pair of spaced contacts engageable by said enlargement when the rod is shifted whereby to dispose the disk of the rod behind the first mentioned disk, and magnetically operable means for rotating the sleeve and shaft whereby the disk may be rotated to dispose its notch out of alignment with the disk of the rod, whereby to prevent return of said rod to former position thereby retaining the contacts in closed position.

3. A subscriber's set for lock out party line telephone systems, including a casing having an opening in its front wall, a dial plate covering said opening, and having a central opening therein, a shaft mounted for rotation and extending through said opening, a hand carried by the extremity of said shaft for movement across the face of the dial, a disk stationarily mounted within the casing, a plurality of pairs of spaced contacts arranged circumferentially around the disk, a contact arm fixedly carried by said shaft for engagement with one disk of each pair, a sleeve encircling the shaft in insulated relation thereto, a second contact arm carried by the sleeve for engagement with the other contacting pair, a disk carried by said sleeve having a peripheral notch, a rod slidably mounted in a direction axially of the disk, a circular enlargement carried by said rod for movement through the notch, a second enlargement carried by the rod, a pair of normally spaced contacts engageable by the second enlargement when the rod is moved, one of said contacts acting to urge the rod forwardly to normally retain the enlargement at one side of the disk, a ratchet wheel carried by the sleeve, a pawl mechanism for rotating the ratchet wheel, an electromagnet for actuating the pawl, a contact finger engaging the sleeve, and a second contact finger engaging the shaft.

In testimony whereof I affix my signature in presence of two witnesses.

FRANK L. GOHEEN.
